DOOR HINGE

Emil A. Zetmeir, Topeka, Kans.

Application October 13, 1934, Serial No. 748,175

3 Claims.

My invention relates more particularly to what is known as a floor hinge for a two-way swinging door of the type generally employed between dining rooms and pantry and as inner doors at the ends of the main aisles of Pullman cars.

The object of my invention is to provide an easy and noiseless operating door hinge wherein the weight of the door is carried by a rotative portion of the hinge which has anti-friction bearing relation with the floor engaging base or foot portion.

Another object of my invention is to provide a dirt and water-proof construction which requires no adjusting screws or other elements which are apt to work loose and interfere with the proper operation of the door.

A further object of the invention is the provision of a construction wherein the moving parts may be immersed in oil thus ensuring constant lubrication of the movable parts and the noiseless operation of the hinge.

The above enumerated objects and the advantages inherent in the construction will all be more fully comprehended from the following detailed description of the accompanying drawing wherein:

Figure 1 is a sectional elevation of portions of a door and door-casing with parts broken away and showing the application of my improved hinge.

Figure 2 is a cross sectional view taken substantially on the line 2—2 of Figure 1.

Figure 3 is a sectional view taken substantially on the line 3—3 of Figure 2.

Figure 4 is a detail perspective view of the top cap member of my improved hinge.

Figure 5 is a detail perspective of the roller bearing holding ring.

Figure 6 is a detail perspective of the bottom cap or supporting member.

My improved hinge is intended for doors adapted to swing in opposite directions and wherein the hinge is intended to be secured to the floor to carry the entire weight of the door; while the door is intended normally to be returned to closed position.

In the particular exemplification, portions of a door are shown at 10; the upper part of the door adjacent its rear edge being preferably provided with an apertured plate 11 adapted to receive a short pin 12 secured to the top frame member 13; the pin permitting the door to swing thereabout in either direction from the closed position shown in Figure 1; the side member of the door-frame being indicated at 14.

The lower rear end of the door is cut away or

(CL. 16—185)

socketed to receive a shell or casing 15 which is vertically disposed and has its wings or walls 16, 16 secured to opposite sides of the door; the rear wall of the casing being shown arcuate to conform with the usual curved rear edge of doors of this general character.

Within the semi-circular or arcuate portion of the casing 15 is an outer cylindrical member or tube 17 whose interior at the lower end is threaded and screws on to the externally threaded portion 10 of the supporting member 18. This supporting member 18 is shown in Figure 6 and comprises the floor engaging flange 19 shown provided with screw-holes whereby the member may be immovably secured to the floor as shown in Figures 1 15 and 3. The upstanding portion of the member 18 is externally threaded at 20 as previously stated to receive the outer tube 17; while the upper end above the threads is reduced to provide a shoulder 21, and the top is provided with a transversely disposed deep slot 22.

The slot 22 is intended to receive the bent lower end 23 of a coil spring 24; while the annular shoulder 21 is intended to support the anti-friction means consisting of the ball bearings 25, and 25 race-way members 26, 26, see Figure 3.

Annular members 26, 26 are each provided with an annular groove 27 (see Figure 5) to receive the balls 25 and top member 26 supports the lower end of an inner tube 28 which encases the 30 spring 24. The race-way providing members 26, 26 are also each provided with a circular hole 29 disposed therethrough for passage of the lower bent end 23 of the coil spring 24 so the two members 26 may rotate about the bent end 23 and fit 35 about the reduced upper end of the base member 18.

The upper end of tube 28 is threaded on its interior and screws onto the threaded portion 30 of a top cap member 31; the member 31 being 40 preferably provided with an annular flange 32 adapted to form an abutment for the upper end of inner tube 28 and to also lap the upper end of outer tube 17. The top of cap member 31 is 45 preferably provided with an upstanding boss portion 33 which is of angular or non-circular cross-section and adapted to fit into a non-circular socket in a plate 34 which is adapted to fit snugly between the side walls 16, 16 of the casing 15, to 50 which it may be secured; the side walls 16, 16 of the casing holding the plate or block 34 against rotative movement.

The lower end of cap member 31 is shown provided with a transverse slot 35 which is intended 55

to receive the upper bent end 36 of the coil spring 24, as shown in Figure 3.

It is apparent that with the angular or non-circular boss 33 of cap member 31 inserted in the non-circular hole of plate 34, cap member 31 will be held against rotation about its axis; and with the upper end 36 of coil spring 24 in the slot 35 of cap member 31, while the lower end 23 of the spring is in the slot 22 of the immovable supporting member 18, rotation of the spring about its axis is impossible and the spring therefore placed under torsional strain when the door 10 is swung to either side of its normal vertical plane. It is evident, therefore, that as soon as the door is released the torque of the spring will be imparted to the door 10 through cap member 31 and its non-circular boss 33 to the plate member 34 secured to the door.

Disposed between the sides 16, 16 of the casing 15 and preferably intermediate of the top and the bottom thereof is a horizontally disposed casing 37 provided with a closed end 38 which has a threaded opening to receive the threaded pin 39 of a compression member 40 whose inner end 25 receives and bears on a coil spring 41; the outer end of the pin 39 being preferably provided with a suitable head 42 whereby the pin may be more easily rotated.

The other open end of the casing 37 is provided with a roller carrying block 43 against which the inner end of coil spring 41 bears, causing the block 43 to be yieldingly forced toward the open end of the casing 37 and hence into proximity with the outer tube 17. The block 35 43 is slotted to receive a roller 44 which is rotatably held in place in the block by a suitable pin 45; the roller being of a size, or so mounted in the block, that its perimeter will extend beyond the end of the block 43 as shown in Figures 2 and 3. The block 43 is non-rotatably held in the casing 37 by means of a pin 46 which is secured to the block 43 and is adapted to ride in a slot 47 in the side of casing 37. The casing 37 is inserted in a suitable socket formed in the door 40 10 and is held in position by some of the screws whereby the side walls or plates 16, 16 of the main casing 15 are secured to opposite sides of the door 10.

The outer tube member 17, at a point coincident with the horizontal plane of the roller 44, is provided with an annular rib or flange 48 (more clearly shown in Figure 2) which, at pre-arranged points on its perimeter, has the depressions or sockets 49.

55 These sockets are adapted to form seats for the roller 44. As the tube 17 is secured to the supporting floor member 18, tube 17 will not rotate during swinging movement of the door and as the annular socketed flange 48 is integrally 60 united with the tube 17 it is apparent that when the door is swung sufficiently to either side, the roller 44 will ride onto the main perimeter of the flange 48, while the block 43 moves inwardly against the action of the spring 41; this 65 movement of the block being possible because of the slot-and-pin relation between block 43 and the casing 37. The spring 41 causes the door to be constantly under more or less tension thus causing the door to remain in its closed 70 position with the roller 44 in one of the sockets 49 of the flange as shown in Figure 2; or to remain in a complete open position when the roller 44 is either in the socket 49 at the top or socket 49 at the bottom of the structure as viewed in 75 Figure 2; namely when the door has been swung

approximately ninety degrees to the right or to the left of its central or closed position.

With the lower end 23 of the spring 24 inserted in the immovable floor member or pedestal 18, it is apparent that the spring 24 will be placed 5 under torsional or twisting strain—either in a winding or unwinding direction—which induces the door to return to closed position as soon as the roller 44 has been moved out of a socket 49; the spring 24 being in normal condition when 10 the door is closed.

The rear arcuate wall of the shell or casing 15 is formed with a slight bulge at 58 to provide sufficient space for the arcuate flange 48.

The tube 17 is secured at its lower end to the 15 floor member or pedestal 18, by means of a set screw 51 which will prevent tube 17 unscrewing and inner tube 28 is held against rotative movement on top member 31 by suitable set screw 52. Oil or other proper lubricant may be put into 20 inner tube 28 before the top member 31 has been put into place; tube 28 being filled with a suitable lubricant. Lubrication for the ball bearings will flow from tube 28 through the top bearing member 26 and will also pass through holes 25 53 in the inner tube 28, and into the outer tube 17 which will also direct lubricant toward the ball-bearings and thus provide lubrication for an indefinite period of time and thereby present a noiseless door supporting hinge. At the same 30 time it is apparent that a dirt and water-proof construction is also provided; a construction requiring no adjustment as the usual adjusting screws are eliminated and hence there are no screws to work loose. 35

The construction shown and described is believed to be the simplest and best embodiment of my invention which I have described in terms employed merely as terms of description and not as terms of limitation, as structural modifications are possible and may be made without, however, departing from the spirit of my invention. 40

What I claim is:

1. A hinge of the character described comprising a supporting member adapted to be secured to the floor and provided with an upstanding spring-end holding portion; a coil spring vertically disposed with its lower end associated with said holding portion of the supporting member, a member immovably secured to the door at the upper end of the spring and adapted to receive the upper end of the spring; a tubular casing disposed about the spring intermediate of the two members and secured at its upper end to the last mentioned member so as to move therewith while its lower end has rotative bearing relation on said supporting member, whereby the door is rotatably supported in place, and a casing adapted to fit about the tubular casing, 60 the second mentioned member, the upper end of said supporting member and to lap the opposite sides of the door and be immovably secured thereto, whereby the door is held against lateral displacement. 65

2. A hinge of the character described comprising a supporting pedestal adapted to be immovably secured to the floor and provided in its top with a socket; a coil spring vertically disposed above the pedestal with its lower end seated in 70 said socket so as to prevent bodily movement of the spring; a flanged member immovably secured to the door at the upper end of said spring, the portion of the member beneath the flange being threaded and the lower end provided with 75

a transverse slot adapted to receive the upper end of the spring so as to cause the spring to be twisted when the door is swung in either direction; a spring enclosing tubular casing internally threaded at its upper end to screw onto the threaded end of said flanged member and be secured thereto against rotation; anti-friction bearings disposed about the pedestal and adapted to provide supporting relation for the lower 10 end of said tubular casing; and an enclosing casing adapted to extend about the rear edge of the door, about the upstanding portion of the pedestal and to lap the opposite sides of the door and be secured thereto whereby laterally shifting movement of the lower end of the door is 15 prevented.

3. A hinge of the character described comprising a pedestal member adapted to be immovably secured to the floor and provided with a circumferential shoulder below its top while the 20 top is provided with a transverse slot; a ball bearing race-way mounted on said shoulder; a member adapted to be secured to the door in spaced relation above the pedestal member, said second 25 mentioned member having a portion whereby it

is secured to the door so as to move therewith and also having an annular shoulder and a threaded lower end, the bottom of said member having a transverse slot; a vertically disposed coil spring whose lower end enters the slot in the pedestal member while its upper end enters the slot in the second mentioned member whereby the spring is given a torsional twist when the door is swung in either direction and the door when released returned to closed position; a door supporting tube disposed about the spring with its upper end secured to the threaded end of the second mentioned member while the lower end of said tube is supported by the ball-bearing race-way, said tube being adapted to hold a lubricating medium and having outlet openings in the sides; and a tubular member secured to the pedestal member against rotation and disposed about the door supporting tube and the ball bearing race-way and adapted to receive lubricant issuing through said outlet openings in the door supporting tube and to convey the same toward said ball bearing race-way.
